ROLLER SCREEN

Hughbert M. Lockhart, Highland Park, Mich.

Application March 4, 1949, Serial No. 79,630

6 Claims. (Cl. 160—30)

1

My invention relates to a new and useful improvement in a roller screen adapted for mounting on a window and so constructed and arranged that as the sash of the window is moved from closed position the screen will be unrolled to cover the open space.

It is an object of the present invention to provide a roller screen so constructed and arranged that it may be used on windows of different widths.

Another object of the invention is the provision of a roller screen so constructed and arranged that the buckling or wrinkling of the screen will be prevented should the sash, in moving from closed to open position, become "cocked" to one side or moved out of its normal position.

Another object of the invention is the provision, in a roller screen of this type, of a housing so constructed and arranged as to maintain the screen in close engagement with an abutting member so as to form a tight connection.

Other objects will appear hereinafter.

It is recognized that various modifications and changes may be made in the detail of structure illustrated without departing from the invention, and it is intended that such shall be embraced within the scope of the claims which form a part hereof.

Forming a part of this specification are drawings in which:

Fig. 1 is a perspective view of a window showing the invention applied.

Fig. 2 is an elevational view of a window shown in fragment, illustrating the invention applied.

Fig. 3 is an enlarged sectional view taken on line 3—3 of Fig. 2.

Fig. 4 is an elevational view of the invention showing it applied to a window illustrated in fragment, with a part of the invention broken away.

Fig. 5 is a fragmentary sectional view taken on line 5—5 of Fig. 2.

Fig. 6 is an enlarged sectional view taken on line 6—6 of Fig. 2.

Fig. 7 is a view taken on line 7—7 of Fig. 5, with parts broken away.

In the drawings I have illustrated the invention used with a window which is mounted in a window frame embodying the sides 9 and 10, the top 11, and the bottom 12. Slidably mounted in this window frame is a pair of window sashes, each having a pane of glass 14 and 15, one of these sashes being the upper and the other being the lower. The lower one is indicated as having a bottom rail 16 and side rails 17 and 18. The

2

side rails of the sashes slide between the stops 13, which are mounted on the inner face of the sides 9 and 10 of the frame. Mounted on a pair of these stops 13 at the lower portion thereof are metal strips embodying a portion 19 which is nailed or otherwise suitably secured to the stops 13 and an angularly turned portion 20 which is extended to overlie the side rails 17 and 18, these metallic strips being L-shaped.

10 I provide an enclosing housing for the roller embodying the outer wall 21, a top wall 22, and an inwardly turned flange 23 extending downwardly from the top wall. The bottom wall 24, which is turned inwardly from the front wall 21, is provided with the upwardly turned flange 25. At opposite ends of the structure I provide an end wall 26 having the inwardly directed tongues 27 which are secured to the top and bottom walls 22 and 24 respectively by means of screws 28. As 15 shown in Fig. 5, these end walls 26 are of greater width than the depth of the housing so that the end walls project beyond the edges of the top wall and bottom wall.

20 Mounted within the housing is a roller 31 having the trunnions 31a projecting outwardly from opposite sides and engaging the end walls of the housing. This roller is of the spring-operated type such as the ordinary shade roller, and a detailed construction of the spring arrangement is 25 not deemed necessary. The spring is used for winding the flexible member on the roller in the manner of the ordinary shade roller, excepting that the ratchet mechanism of the ordinary shade roller is eliminated, so that the spring of 30 the roller used maintains constant tension on the screen. In this manner, the screen which is wound upon the roller is always kept stretched taut. Secured at one end to the roller 31 and adapted for winding thereon is a flexible screen 32. On the free edge of this screen 32 is clamped a reenforcing strip, which is rigid and preferably 35 formed from metal and which comprises the clamping brace 33 engaging at opposite sides of the screen and angularly turned, doubled over portion 34, to provide a strip for slipping under the spring clip 35, which is offset from the bottom 40 12 of the frame and has a portion 37 suitably secured to this bottom 12 of the frame. The construction is such that when the reenforcing strip 45 on the screen 32 is inserted beneath the spring portion 35, which has the upwardly turned clamp 36, the reenforcing strip is held firmly 50 against the face of the member 12.

55 Mounted on the sash rail 16, on the interior thereof, is a plate 38, the upper portion 39 of

which is outwardly offset. This outward offsetting is so formed that there is provided a curved shoulder or curvilinear portion 40, against which the edge of the flange 23 rests.

Mounted on the bottom of the bottom rail 42 of the upper sash and projecting inwardly so as to engage the face of the window glass 15, is a strip 41 of suitable flexible material such as rubber, and which extends for the full width of the glass 15. This construction is such that when the lower sash is raised as shown in Fig. 3, the space between the pane of glass 14 and the rail 42 will be closed so that the entry of flies into this space is prevented.

In use the structure is mounted on the window as indicated, and when the lower sash is raised, the screen will be unwound from the roller; and when the lower sash is lowered, the screen will wind onto the roller. The metallic members 20 will always overlie the edges of the screen, and this screen will be kept in contact with these edges, as clearly indicated. As clearly shown in Fig. 6, the structure has a clearance at opposite sides so that it may be used for windows of various widths within certain limitations. Should the lower sash become "cocked" or twisted out of its normal position so that the rail 16 will not be in horizontal position as shown in Fig. 4, the housing will still remain in horizontal position, as this housing will rock on the curved shoulder 40. Frequently the window becomes twisted so that the lower rail is not horizontal when the sash is raised, and when this is effected and the housing mounted fixedly on the lower rail 16, there would be a buckling or wrinkling of the screen at one of its side edges, while the other side edge would lie tight against the member 20. To avoid this, the rockable mounting of the housing is resorted to.

In Fig. 4 the sash is indicated in full lines as being twisted out of its normal position so that the rail 16 does not extend horizontal to the sill 12. Its normal position, in which the rail 16 is horizontal to the sill 12, is indicated by dotted lines.

As the window is lowered and raised, the edges of the side walls 26 will ride along the plates 20. As clearly shown in Fig. 5, the clearance between these wear plates 20 and the upwardly curled edge 25 of the lower wall 24 is the thickness of the screen, so that the screen is thus kept in close contact with the surfaces of the wear plates 20. Moreover, by having the bottom 24 curled upwardly as at 25, a round surface over which the screen rides is provided, thus avoiding any undue wear on the screen when the raising and lowering is effected.

A roller screen of this class has proven most efficient, and it is believed obvious that the housing may be easily and quickly mounted on the lower rail of the sash 16 and easily and quickly attached to and detached from the sill or lower portion of the frame.

Formed in one edge of the side walls 26 is a notch 29 in which the edge of the reenforcing strip engages, so as to prevent this strip from being rolled into the housing when the screen is loose from the sill and wound on the roll. This also leaves the strip accessible for unwinding the screen and also prevents binding of the reenforcing strip on the window frame when the window is raised or lowered while the screen is detached from the sill.

What I claim is:

1. In a roller screen of the class described,

adapted for use with a window sash slidable in a window frame and having a rail extending transversely of said frame, a housing; a roller screen mounted in said housing; attachment members for attaching one end of said screen to said frame for securing said screen and unrolling the same upon movement of said sash in one direction relatively to said frame; and a supporting member on said sash for supporting said housing, said housing being longitudinally tilttable on said supporting member relatively to said sash.

2. In a roller screen of the class described, adapted for use with a window sash slidably mounted in a window frame and having a rail extending transversely of said frame, a housing having a front wall, a top wall, and a bottom wall; an end wall at each end of said housing, said end walls projecting rearwardly beyond the edges of said top wall and bottom wall substantially the thickness of a screen used; a roller mounted upon and extending between said end walls and contained within said housing and extending substantially from end to end thereof; a plate mounted on opposite sides of the window frame and projecting inwardly beyond the ends of said housing; a screen windable on said roller and extending substantially from end to end thereof and adapted for attachment at its outer end to said frame; a supporting member on said sash for supporting said housing thereon, said housing moving upwardly and downwardly with said rail and said end walls, at the edges of their projecting portions, engaging said plates in slidable movement of said window sash and said screen engaging at one of its faces with said plates.

3. In a roller screen of the class described, adapted for use with a window sash slidably mounted in a window frame and having a rail extending transversely of said frame, a housing having a front wall, a top wall, and a bottom wall; an end wall at each end of said housing, said end walls projecting rearwardly beyond the edges of said top wall and bottom wall; a roller mounted upon and extending between said end walls and contained within said housing; a plate mounted on opposite sides of the window frame and projecting inwardly beyond the ends of said housing; a screen windable on said roller; an attachment means for attaching the outer end of said screen to said frame; a supporting member carried by said sash for supporting said housing thereon, said housing moving upwardly and downwardly with said rail and said end walls engaging said plate in slidable movement of said window sash, said housing being mounted on a transverse axis and rockable relatively to said rail when mounted on said sash.

4. In a roller screen of the class described, adapted for use with a window sash slidably mounted in a window frame and having a rail extending transversely of said frame, a housing having a front wall, a top wall, and a bottom wall; an end wall at each end of said housing, said end walls projecting rearwardly beyond the edges of said top wall and bottom wall; a roller mounted upon and extending between said end walls and contained within said housing; a plate mounted on opposite sides of the window frame and projecting inwardly beyond the ends of said housing; a screen windable on said roller; an attachment means for attaching the outer end of said screen to said frame; a supporting member carried by said sash for supporting said housing thereon, said housing moving upwardly and downwardly with said rail and said end walls engaging said

plate in slidable movement of said window sash, said housing being mounted on a transverse axis and rockable thereon relatively to said rail when mounted on said sash, the opposite edges of said screen overlying said plate.

5. In a roller screen of the class described, adapted for use with a window sash slidably mounted in a window frame and provided with a rail extending transversely of the frame, a housing; a roller mounted in said housing; a screen member windable upon said roller; attachment members for attaching the outer edge of said screen member to a stationary body; a supporting member on said rail for supporting said housing thereon, said supporting member having a curvilinear portion upon which said housing may rock, said housing being movable in unison with said sash.

6. In a roller screen of the class described adapted for use with a window sash slidably mounted in a window frame and said sash having a rail extending transversely of said frame; a

housing having a front wall, a top wall, a bottom wall and an end wall at each end of said housing; a roller mounted upon and extending between said end walls and contained within said housing; a screen windable on said roller; an attachment means for attaching the outer end of said screen to said frame; a supporting member on said rail for supporting thereon said housing at a point intermediate its ends in tiltable relation, on a transverse axis of said housing, to said rail.
